QUICK BREAKING THERMAL RELAY

Jacob H. Rubenstein and Lawrence J. De
Martino, Syracuse, N. Y.

Application July 25, 1940, Serial No. 347,508

10 Claims. (Cl. 200—122)

This invention relates to thermally operated relays wherein the contacts are actuated by a thermostatic bar, usually of bi-metallic construction. The thermostatic bar flexes or bends upon the application of heat thereto as by a resistance coil encircling the bar. The amount of movement of the bar and the time required for such movement depends upon the construction of the bar and the amount of heat applied thereto. After the application of heat ceases, it usually requires a like or greater length of time for the bar to pass through its retrograde movement. Because of this characteristic of the device, it is not suitable for use in instances where it is desired to separate the contacts immediately, or substantially immediately, upon the cessation of current to the heating coil of the thermostatic bar.

If an attempt is made to adjust the contacts in order to effect engagement of the same just prior to the interruption of the current to the heating coil, the contact pressure between the contacts is very slight, often causing a fluttering at the contacts, or otherwise making a poor engagement. Even with such adjustment of the contacts, the device can not be used in a situation where it is desired to maintain the circuit through the heating coil closed over a substantial period of time, and to effect immediate separation of the contacts when the heating circuit is interrupted.

This invention has as an object a quick breaking or opening thermal relay embodying a particularly economical and unique structure permitting the current in the heating coil to be left on for an indefinite period of time, but whereby the contacts are disengaged almost immediately when the circuit to the heating coil of the thermostatic bar is interrupted.

The invention consists in the novel features and in the combinations and constructions herein-after set forth and claimed.

In describing this invention, reference is had to the accompanying drawing in which like characters designate corresponding parts in all the views.

Figure 1 is a top plan view of a thermal relay embodying our invention.

Figure 2 is a side elevational view of the structure shown in Figure 1 with parts shown in section, the section being taken on line 2—2, Figure 1.

Figure 3 is an end elevational view looking to the left Figure 1, with parts shown in section.

Figure 4 is an elevational view of the motion

transmitting member cooperable with the contact arms.

Figure 5 is a side elevational view of a modified form of our invention with parts shown in section.

Figure 6 is a fragmentary view illustrating the relative position of the thermostatic arm shortly after the engagement of the contacts.

Figure 7 is a view, similar to Figure 6, illustrating the position of the thermostatic arm subsequent to the engagement of the contacts and during the continued application of heat to the arm.

Figure 8 is a view, similar to Figures 6 and 7, illustrating the position of the thermostatic arm subsequent to the disengagement of the contacts.

The invention consists generally in a suitable support or base, a contact arm and a thermostatic bar or arm. One of these arms is journaled at one end to the support and is frictionally retained against movement. Complemental contacts are carried by the free ends of the arms, and the arrangement is such that upon the application of heat to the thermostatic arm, the normally spaced contacts are moved into engagement, and upon the continued application of heat to the thermostatic arm the movable arm is moved about its pivot. The free ends of the arms are connected by a lost motion member which is operable to permit engagement of the contacts and to limit the maximum spacing between the contacts. Upon the cessation of heat to the thermostatic arm, the contacts are immediately, or substantially immediately, separated and as the arm cools off retrograde movement of the movable arm is effected until the parts return to their initial position.

The support or frame here shown is provided with a base 10, an upwardly extending flange 11, and a laterally extending flange 12. In the form shown in Figures 1, 2 and 3, a shaft 13 is rotatably journaled in the upright 11 and is formed at one end with an enlarged head portion 14 and is threaded at the opposite end to receive a nut 15 cooperable with a washer 16 to compress spring 17 in order to frictionally restrain the shaft 13 against rotation. It will hereafter be apparent that the frictional restraint of the shaft 13 need only be slight. Sufficient friction may be obtained by making the shaft a close fit in the aperture in which it is journaled. However, we prefer the arrangement of the spring 17 and adjusting nut 15 in order to provide for convenient adjustment of the shaft 13.

In this form, the contacts are carried by arms 18, 19. The arm 19 is formed of relatively thin

and flexible metal and is mounted upon a block of insulating material 20 arranged on the flange 12. The arm 19 extends transversely of the flange and is provided at its free end with a contact 21. The fixed end of the arm 19 may be provided with a suitable terminal screw 22 by means of which a load circuit conductor 22^a may be electrically connected to the arm.

The arm 18 is formed of relatively thick metal and is mounted at one end on a block of insulating material 23 superimposed upon the block 20 and the fixed end of arm 19. The assembly is rigidly clamped together and secured to the flange 12, as by screws 24, the arms 18, 19 being insulated from each other and from the screws 24 by means of insulating washers 25 as is conventional in electrical apparatus of this type. The rigid arm 18 is provided with a contact 29 and a suitable terminal screw 27 for the attachment of the load conductor 28 to said arm.

The thermostatic bar or arm is indicated at 30 and may be of conventional bi-metallic construction. The arm 30 is secured to the enlarged head portion 14 of the shaft 13 as by screw 31, and the bar is encircled by a suitable heating coil 32 which, when energized, is operable to apply heat to the bar to effect a flexing thereof.

The free end of the bar 30 is operatively connected to the arms 18, 19 by a motion transmitting member in the nature of a block of insulating material 35. The block 35 is provided adjacent one end with an aperture 36 to receive the free end of the bar 30, and adjacent its opposite end with an opening 37 of sufficient width to receive the ends of the arms 18, 19 and to permit the contacts 21, 29 to be normally arranged in spaced apart relation.

When the coil 32 is energized, and accordingly heat is applied to the arm 30, the free end of the arm flexes upwardly or toward the arm 18. This movement also effects movement of the arm 19 toward the arm 18 through the instrumentality of the block 35, and the contacts 21, 29 are moved into engagement, as illustrated in Figure 6.

Upon the continued energization of the coil 32, the bar 30 continues to flex but inasmuch as the contacts 21, 29 are now in engagement, the free end of the bar 30 can not move upwardly any further and accordingly, rotation of the shaft 13 is effected. When the heating coil 32 is deenergized, the bar 30 moves to straight normal position, as illustrated in Figure 2. The first part of this movement however takes place at the free end of the bar due to the fact that the shaft 13 is frictionally restrained against movement. Accordingly, the contacts 21, 29 almost immediately move out of engagement and this movement continues until the top portion of the block 35 engages the top surface of the rigid arm 18. Thereafter, retrograde movement of the free end of the bar 30 is arrested, as illustrated in Figure 8. Thereafter the straightening movement of the bar 30 effects retrograde movement of the shaft 13.

In Figure 5, one end of the bar 30 is rigidly secured to the support as by screw 38 which also serves as a means of connecting the load conductor 22^a to the bar. The bar is, of course, 70 suitably insulated from the support.

The relatively rigid or inflexible bar 18 is mounted, at one end, to a similar shaft 13 journaled in the support. In this modified form, the flexible arm 19 is omitted and the contact 21 75

secured directly to the free end of the bar 18, and the insulating block 35 is formed with appropriate dimensions for this arrangement. In this structure, the bar 30 is operable to move the contacts 21, 29 into engagement upon energization of the coil 32 and, upon the continued application of heat, the arm 18 is moved about the axis of the shaft 13 to which it is connected. When current is discontinued to the heating coil 10 32, the first movement of the free end of the bar 30 effects separation of the contacts 21, 29 and thereafter the arm 18 is moved in retrograde direction by the block 35 as will be readily apparent.

15 While we have described specific structures to illustrate our invention, it will be apparent that numerous changes can be made in this structure without in any way omitting the subject matter of our invention. For example, the support may 20 be of any suitable form or construction and the contact arm 19 may be omitted in the structure shown in Figures 1 to 3, and the contact 21 carried directly by the free end of the bar 30, as illustrated in Figure 5.

25 It will be observed that we have devised a thermally operated relay which is self compensating in a manner whereby upon cessation of heat to the thermostatic element, the contacts are quickly separated regardless of how long the 30 heat has been previously applied to the element. This structure has proven to be particularly efficient and economical in devices requiring a large number of thermal relays, such as for example pin-ball machines.

35 What we claim is:

1. A quick breaking thermal relay comprising a support, a contact arm, a thermostatic arm, a member rotatably journaled in said support and frictionally restrained against rotation, one 40 of said arms being rigidly mounted at one end on said support and said other arm being mounted at one end on said rotatable member, contacts associated with the free ends of said arms and being normally arranged in spaced relation, said thermostatic arm being operable upon the application of heat thereto to move said contacts into engagement, means operable to apply heat to said arm, and means cooperable with the free ends of said arms to limit the maximum spacing 45 between said contacts.

2. A quick breaking thermal relay comprising a support, a contact arm, a thermostatic arm, a member rotatably journaled in said support and frictionally restrained against rotation, one of 50 said arms being rigidly mounted at one end on said support and said other arm being mounted at one end on said rotatable member, contacts associated with the free ends of said arms and being normally arranged in spaced relation, said thermostatic arm being operable upon the application of heat thereto to move toward said contact arm to move said contacts into engagement and upon the continual application of heat to effect rotation of said rotatable member, and said thermostatic arm being operable upon the cessation of heat thereto to return said contacts to normal position and thereafter effect retrograde movement of said rotatable member, and means operable to apply heat to said thermostatic arm.

3. A quick breaking thermal relay comprising a support, a contact arm, a thermostatic arm, a member rotatably mounted in said support and being frictionally restrained against rotation, one 65 of said arms being rigidly mounted at one end

on said support and said other arm being mounted at one end on said rotatable member, complementary contacts carried by the free ends of said arms and being normally arranged in spaced relation, a motion transmitting member cooperable with the free ends of said arms to permit movement of one arm toward the other to effect engagement of said contacts and to limit the maximum spacing between said contacts, said thermostatic arm being operable upon the application of heat thereto to move the free end thereof toward said contact arm and to move said contacts into engagement and upon the continued application of heat to effect rotation of said rotatable member, a heating coil arranged in juxtaposition to said thermostatic arm and operable to apply heat thereto, and said thermostatic arm being operable substantially immediately upon the cessation of heat thereto to move said contacts in normal position and to subsequently effect retrograde movement of said rotatable member.

4. A quick breaking thermal relay comprising a support, a rigid contact arm mounted on said support, a member rotatably journalled in said support and frictionally restrained against rotation, a bi-metallic arm secured at one end to said rotatable member, contacts associated with the free ends of said arms and being normally arranged in spaced relation, a heating coil arranged in juxtaposition to said bi-metallic arm and being operable when energized to apply heat to said arm, said bi-metallic arm being operable upon the application of heat thereto to move the free end thereof toward said rigid arm and move said contacts into engagement and to subsequently effect rotation of said rotatable member, and said bi-metallic arm being operable upon deenergization of said coil to substantially immediately effect disengagement of said contacts and to subsequently effect retrograde movement of said rotatable member, and means cooperable with the free ends of said arms to limit the maximum spacing between said contacts.

5. A quick breaking thermal relay comprising a support, a contact arm journalled at one end to said support and being frictionally restrained against movement, a thermostatic bar rigidly secured at one end to said support, the free ends of said arm and bar being provided with complementary contacts normally arranged in spaced relation, a motion transmitting member cooperable with the free ends of said arm and bar to limit the maximum spacing between said contacts and to permit engagement of said contacts, a heating coil encircling said thermostatic bar and being operable when energized to apply heat to said bar, and said bar being operable upon the application of heat thereto to move the contact carried thereby into engagement with said other contact and upon the continual application of heat to effect movement of said contact arm about its pivot, and said bar being operable upon the deenergization of said coil to substan-

tially immediately move said contacts out of engagement and to subsequently effect retrograde movement of said contact arm.

6. A quick breaking thermal relay comprising a support, a rigid contact mounted on said support, a member rotatably journalled in said support, a thermostatic bar secured at one end to said rotatable member and being provided at its opposite end with a contact, means cooperable with said bar and rigid contact to limit the maximum spacing between said contacts, said bar being operable upon the application of heat thereto to move the contact carried thereby into engagement with said rigid contact, and to subsequently effect rotation of said rotatable member.

7. A quick breaking thermal relay comprising a support, a rigid contact carried by said support, a flexible spring contact carried by said support and normally spaced from said rigid contact, a member rotatably mounted in said support, a thermostatic bar secured at one end to said rotatable member, means cooperable with said bar and said contacts to effect movement of the flexible contact into engagement with said rigid contact upon the application of heat to said thermostatic bar, and to limit the maximum spacing between said bar and said rigid contact.

8. A quick-acting thermal relay comprising a support, a contact mounted on the support, a thermal responsive member movably mounted at one end on said support and frictionally restrained against movement relative to the support and being operable upon change in temperature to move into and out of engagement with said contact, and means cooperable with said contact and said thermal responsive member to limit the spacing therebetween to a predetermined maximum.

9. A quick-acting thermal relay comprising a support, a contact, a thermal responsive member movably mounted at one end to said support and being frictionally restrained against movement relative to the support, the free end of said thermal-responsive member being operable upon change in temperature of said member to move into and out of engagement with said contact, and means cooperable with said thermal responsive member to limit the spacing between said contact and said member to a predetermined maximum.

10. A quick-acting thermal relay comprising a support, a pair of contacts, a member rotatably mounted in said support and being frictionally restrained against rotation, a thermal responsive member mounted on said rotatable member, the free end of said thermal responsive member being operable upon change in temperature to move said contacts into and out of engagement, and means cooperable with said thermal responsive member to limit the spacing between said contacts to a predetermined maximum.
